Patented May 17, 1966

204,760

CARD PUNCH AND VERIFIER OR THE LIKE

William N. Brownfield, Berwyn, and John C. Schulte,
Maple Glen, Pa., assignors to Sperry Rand Corporation,
New York, N.Y., a corporation of Delaware

Filed Apr. 9, 1965, Ser. No. 84,707

Term of patent 14 years

(Cl. D26—5)

FIG. 1

Des. 204,760

PAGE 5

FIG. 4

FIG. 5

FIG. 6

FIG. 1 is a front perspective view of a card punch and verifier showing our new design;

FIG. 2 is a rear perspective view thereof;

FIG. 3 is a side elevational view thereof;

FIG. 4 is a front perspective view of the card punch and verifier of FIG. 1 showing a modified embodiment thereof;

FIG. 5 is a rear perspective view thereof;

FIG. 6 is a side elevational view thereof.

We claim:

The ornamental design for a card punch and verifier or the like, as shown.
